(57) **CLAIM**

The ornamental design for a waste gas scrubber, as shown and described.

DESCRIPTION

FIG. 1 is a perspective view of a waste gas scrubber according to the present invention;

FIG. 2 is a front view of the waste gas scrubber of FIG. 1; FIG. 3 is a rear view of the waste gas scrubber of FIG. 1; FIG. 4 is a left side view of the waste gas scrubber of FIG. 1;

FIG. 5 is a right side view of the waste gas scrubber of FIG. 1;

FIG. 6 is top plan view of the waste gas scrubber of FIG. 1; and,

FIG. 7 is a bottom plan view of the waste gas scrubber of FIG. 1.

The broken lines show portions of a waste gas scrubber which form no part of the claimed design.
